UNITED STATES PATENT OFFICE

2,564,608

HYDRAULIC TRACTOR DRIVE

James S. Robbins, Highland Park, Ill.

Application June 21, 1950, Serial No. 169,408

11 Claims. (Cl. 74—37)

1

The main objects of this invention are to provide an improved form of operating mechanism for endless chain belts, such as are used for heavy-duty conveyors, belt treads of tractors and the like; to provide improved means for transmitting power from a reciprocating piston utilizing both forward and return strokes thereof for driving the belt in the same direction; to provide improved means for reversing the travel of the belt as a whole; and to provide improved means for utilizing hydraulic power for the operation and control of such mechanism as applied to a tractor.

These objects are accomplished by the illustrative embodiments of the invention shown in the accompanying drawings in which:

Figure 1 is a side elevation partly in section of a tractor tread member of the track-laying belt type equipped with operating mechanism constructed according to this invention.

Fig. 2 is a horizontal section of the supporting frame and belt-operating mechanism, taken on the line 2—2 of Fig. 1 but omitting the belt.

Fig. 3 is a side elevation of the device of Fig. 1 but viewed from the back thereof.

Fig. 4 is a fragmentary detail, partly in section and on a somewhat larger scale, of the cross head that carries the latching pawls which engage the belt.

Fig. 5 is a vertical section of the same taken on the line 5—5 of Fig. 4.

Fig. 6 is a sectional detail of the same, taken on the line 6—6 of Fig. 1.

Fig. 7 is a sectional detail, corresponding to Fig. 5, showing a modified form of pawl-shifting mechanism.

Fig. 8 is a section of the same taken on the line 8—8 of Fig. 7.

Fig. 9 is a schematic diagram illustrating the arrangement and operation of a hydraulic system for supplying power to, and for controlling the belt-driving mechanism.

Fig. 10 is a schematic sectional detail of a form of valve suitable for regulating the flow of hydraulic medium to the operating mechanism of a tractor having a pair of tractor belts, such as the one of Fig. 1, located at opposite sides of a vehicle frame.

It is well known that in tractors, having belt treads such, for example, as the tractors of mining machinery for which the subject matter of the drawings is particularly designed, the vehicle frame structure is usually carried by one or more pairs of traction belts in the form of endless chain ground-gripping structures placed side by side.

Figures 1 to 6, inclusive, of the drawings illustrate the structure and operating mechanism of one of such belts and Fig. 9 shows the method of hydraulically controlling a pair of such belts.

2 for simultaneous forward and reverse operation and for operation in respectively different directions and at different speeds relative to each other for the purpose of driving and steering the tractor.

Each belt-carrying frame comprises a pair of plate-like frame members 11 rigidly connected together in parallel relation to each other and provided with suitable tracks for guiding the links of the belt 12 between sprocket wheels 13 at the opposite ends of the frame. A horizontally disposed hydraulic cylinder 14 is rigidly mounted in the frame and has a piston 15 whose piston rod 16 is pivotally connected at 17 to a cross head 18, which is carried by ball bearing rollers 19 and mounted to reciprocate in runways formed by parallel tracks 20, located parallel with and midway between the upper and lower horizontal runs of the traction belt.

The cross head 18 has a pair of connection members in the form of double-acting latch bars 21 mounted to slide vertically therein and both ends of each of these members serve as pawls shiftable to positions for coacting with the spindles 22 or other suitable shoulders of either the upper or the lower run of the belt for driving the belt in either direction of travel. The structure of the cross head and its pawl-operating mechanism is illustrated on a larger scale in Figs. 4 and 5, where it will be seen that the latch members 21 are vertically slidable in guideways formed in the cross head 18. Each member 21 is yieldably positioned for coaction with either run of the belt 12 by a pair of opposed helical springs 23 and 24 seated in grooves 25 in the opposed faces of the members 21. The springs 23 and 24 bear in opposed relation to each other between shoulders 26 on the member 21 and a lug 27 that is carried by a rack bar 28. These rack bars are mounted in ways in the interior of the cross head 18 so as to mesh and coact with a pinion 29 whereby the rack bars are shifted in opposite directions so as to carry their respective pawls into position for coacting with opposite runs of the belt. The members 21 have their outer ends beveled, as shown in Fig. 5, so that each of its pawls drives the chain when the piston moves in one direction and yields against the action of its springs to slip past the rods 22 when the piston moves it in the reverse direction. Thus as the piston reciprocates, one member 21 will drive one run of the belt during one direction of piston movement and the other member 21 will drive the other run of the belt when the piston moves in the reverse direction.

Stop pins 30 extend into grooves 31 in the latch members 21 and the movements of such latch members under the action of their springs 23 and 24 are limited by shoulders at the ends of grooves 31. Thus the pin 30 and groove 31

determine the range of movement of the respective latch member 21 and the position of the lug 27 determines which run of the belt 12 will be engaged by the latch member. In the position shown in Fig. 5, the springs 23 will be under greater compression strain than the springs 24 when the latch members are in the position shown in Fig. 5, and will control the latching action of the pawls. The springs 24 will be likewise under greater compression strain when the position of the racks 28 as reversed by rotation of the pinion 29 and the pawls will then drive the chain in the reverse direction.

The pinion 29 is fast on a shaft 32 journaled in the cross head 18 and in a bracket 33 that extends outward therefrom through an opening 34 in the side frame 11. The shaft 32 has a pinion 35 fast thereon which meshes with a rack 36 actuated by a wire 37 that runs through a flexible tube 37.1 to a convenient position on the vehicle where it can be shifted manually, as for example, by lever 91.1 or 91.2.

The sprocket 13 which carries the traction chain belt 12 at the end of the frame that is at the right in Figs. 1 and 2 and at the left in Fig. 3, is journaled in a cross head 38 that is slidably mounted in guide ways 39 for taking up the slack in the traction belt 12 and this cross head 38 is shifted longitudinally of the frame by a connecting rod 40 driven by the piston 41 of a cylinder 42.

In Fig. 2, the cylinders 14 and 42 are shown partly in section and partly in plan; whereas in Fig. 1, the side plate frames 11 are partly broken away to show these cylinders and their connections with their cross heads in elevation. The cylinder 14 is provided with ports 43 and 44 at its opposite ends for the admission and escape of hydraulic fluid for driving its piston 15 in opposite directions and the cylinder 42 has ports 45 and 46 for the flow of fluid to and from the chambers at the ends of the piston 41. The piping which connects these ports for hydraulic operation of the pistons is not shown in Figs. 1, 2 and 3 but is indicated diagrammatically in Fig. 9.

In Figs. 2 and 3, the valve which controls the reverse movements of the chain-driving piston 15 is indicated at 47 and has a spool 48 which is rotated in its casing to control its ports in well-known ways.

Rotation of the spool 48 in one direction is controlled by a dog 49 coacting with an arm 50 on the spool 48 and reverse rotation of the spool 48 is controlled by a dog 51 that coacts with the arm 52 on the spool 48. The dogs 49 and 51 are adjustably mounted on a rod 53 that is affixed to an arm 54 on the bracket 33 which reciprocates with the cross head 18. The rod 53 is slidably mounted in a stationary bracket 55.

In the modified form shown in Figs. 7 and 8, the driving of the chain belt 12 is accomplished by a single pawl 56 that is shiftable in the cross head 57 so as to engage the spindles 22 of the upper run of the belt, as illustrated in Fig. 7, and to clear those of the lower run of the belt, or to be shifted downwardly to engage the spindles 22 of the lower run of the belt and clear those of the upper run. In this case, the body portion of the cross head 57 is in the form of a hydraulic cylinder 58 and the pawl 56 is in the form of piston rods extending through opposite heads of the cylinder 58 and having a central piston portion 59 that is shiftable by hydraulic pressure at opposite sides thereof.

The cylinder 58 is accordingly provided with ports 60 and 61 controlled by a valve, such as the

valve 41, through the movements of the cross head so as to shift the pawl 56 from one belt run to the other at the opposite ends of the travel of the cross head 57 under the power furnished by the hydraulic cylinder 14.

When the invention is applied to operation of the traction belts of a crawler tractor, there are usually two units placed side by side and rigidly connected together by a suitable frame structure, not shown in the drawings.

An illustrative schematic diagram of hydraulic mechanism for the operation and control of a tractor unit, comprising a pair of such tractor belts, is shown in Fig. 9 of the drawings. In this drawing, the parts of the separate belt systems are designated by the same reference numerals as the corresponding parts shown in the other views of the drawings but are distinguished by characters with decimal suffixes .1 and .2 respectively. The piping as shown comprises main supply lines for the traction cylinders 14.1 and 14.2, a pilot line for controlling the larger valves of the power line to these cylinders, and a third line to the take-up cylinders.

In Fig. 9 the reservoir for the hydraulic fluid supply is designated by the numeral 62. The fluid is drawn from the reservoir 62 by a pump 63 and delivered through pipe 64 to branch pipes 65.1 and 65.2 to the belt driving cylinders 14.1 and 14.2 respectively. Fluid escaping from the cylinders is conducted by pipes 66.1 and 66.2 from which it flows through return pipe 67 back to the reservoir 62.

The pilot valve 41.1 controls the cylinder 14.1 in cooperation with a four-way power line control valve 68.1 for reversing the movement of the piston 15.1 by alternately reversing the connection between the ports 43.1 and 44.1 of the cylinder 41.1 with the pressure line 65.1 and the return line 66.1.

Similarly, valve 41.2 and valve 68.2 control the supply and discharge of operating fluid to the cylinder 14.2 through power pipe 65.2 and return pipe 66.2. The connections to the ports 44.1 and 44.2 are made direct with the pipes 65.1 and 65.2 respectively and the corresponding ports of valves 68.1 and 68.2 are closed by plugs 88.3. This arrangement compensates for the fact that the piston rod occupies part of the cylinder area on one side of the piston and assures that equal total pressures drive the piston in both directions of its movement.

A manually controlled throttle valve 69 controls the amount of power fluid passing from the supply pipe 64 to the pipes 65.1 and 65.2 and thus controls the speed of travel of the belts 12.

The pipes 65.1 and 65.2 are also controlled differentially by a manually controlled valve 70 for steering purposes. A suitable structure for the steering valve 70 is shown schematically in Fig. 10. In the form shown, the power line 64 communicates with a central chamber 71 in the valve casing and the pipes 65.1 and 65.2 connect with chambers 72 and 73 respectively. The flow from the chamber 71 to the chambers 72 and 73 is controlled by a plunger-like spool 74 which slides through a bore 75 extending through the end walls of the valve and the partition walls which separate the chambers 71, 72 and 73. The spool has a contracted neck 76 in its mid-portion with tapered portions 77 and 78 at opposite ends of the neck 76.

These tapered portions 77 and 78 are spaced so that when the spool 74 is in the middle position in which it is shown, equal quantities of liquid

will pass from the pipe 64 to the pipes 65.1 and 65.2. When the spool is shifted toward the right of Fig. 10, the flow of liquid to the pipe 65.1 will be gradually reduced and finally cut off entirely. When the spool is shifted toward the left of Fig. 10, the flow of fluid from pipe 65 to pipe 65.2 will be correspondingly cut off and reduced. Thus by shifting the spool, the relative speeds of travel of the two traction belts can be controlled by manipulating the valve 70.

A by-pass connection 79 between the pipes 64 and 67 controlled by a check valve 80 permits the pump 63 to be operated at a speed somewhat in excess of the demands of the system.

Hydraulic pressure for automatic operation of the valves 68.1 and 68.2 is provided through supply lines 81.1 and 81.2 connected to the pipe 64 and return lines 82.1 and 82.2 connected to the return pipe 67.

A four-way valve 83.1 controls the connection between the pipes 81.1 and 82.1 with alternative extension lines 84.1 and 85.1, which lines are reversed in their relation to the extension lines 86.1 and 87.1 through the shifting of the spool of the four-way valve 47.1.

The pipes 86.1 and 87.1 are each connected to jack means 88.1 for operating the spool of the four-way valve 68.1. The valve 83.1 is controlled manually through the shifting of its spool 89.1 by a cam 90.1 controlled by a hand lever 91.1. The cam 90.1 has angularly spaced high points 92.1 corresponding to the limiting positions of the lever 91.1 and a low point 93.1 midway between the high points 92.1 as indicated by the arrow 94.1.

Levers 91.1 and 91.2 are the same levers, hereinbefore referred to, that operate the control wires 37 in the form shown in Figs. 1 to 5 inclusive or the control valves (not shown) that operate the piston 59 in the form shown in Figs. 7 and 8. The limiting positions of said levers indicated by arrows 94.1 and 94.2 correspond respectively to reverse directions of travel of the traction belts at opposite sides of the vehicle body. The function of the valves 83.1 and 83.2 and cams 90.1 and 90.2 is to reverse or modify temporarily the pressures on the motor pistons 15.1 and 15.2 to reduce the frictional resistance on pawls 21 or 56 and permit them to shift easily for reversing the travel of the traction belts when levers 91.1 and 91.2 are shifted from one limit of their throw to the other.

The control mechanism shown at the right side of Fig. 9 is identical with that shown at the left side and hereinbefore-described and is identified by corresponding numerical characters distinguished by the decimal suffix .2.

The belt tensioning cylinders 42.1 and 42.2 are connected to the pipe 64 by feed pipe 95 through branch lines 95.1 and 95.2, with a by-pass line 96 connecting the pipe 95 to the return flow pipe 67. This by-pass line is controlled by a bleeder valve 97 whereby the pressure on the pistons of the cylinders 42.1 and 42.2 may be regulated. The air chamber 98 allows for some resilience in the take-up effect of the cylinders 42.1 and 42.2.

Although some of the structure shown has been specifically described, it will be understood that numerous details of the structure shown may be altered or omitted without departing from the spirit of the invention as defined by the following claims.

I claim:

1. A chain belt drive, comprising an endless chain belt arranged to provide a pair of parallel

runs moving in opposite directions, a crosshead mounted to reciprocate longitudinally between said runs, and latch means carried by said crosshead and operative to drivingly engage one run of

5 said belt when the crosshead moves in one direction and to drivingly engage the other run of said belt when said crosshead moves in the opposite direction, said latch means comprising a driving element movable on said crosshead from a position for driving one of said belt runs in one direction to a position for driving the other belt run in the same direction, and a second driving element movable on said crosshead between positions for driving said belt runs in the opposite directions, said elements being of ratchet pawl formation adapted to drive the respective belt runs in one direction of travel and to withdraw in the other direction of travel.

2. A chain belt drive, comprising an endless chain belt arranged to provide a pair of parallel runs moving in opposite directions, a crosshead mounted to reciprocate longitudinally between said runs, motor means operative to reciprocate said crosshead, latch means carried by said crosshead and operative to drivingly engage one run of said belt when the crosshead moves in one direction and to drivingly engage the other run of said belt when said crosshead moves in the opposite direction, said latch means comprising a pair of connected ratchet pawls shiftable on said crosshead transversely to the belt runs for alternatively driving them in the direction of travel of the crosshead, a second pair of connected ratchet pawls shiftable on said crosshead transversely to the belt runs for alternatively driving them in the opposite direction of travel of the crosshead.

3. A device of the class described, comprising a chain belt having parallel runs traveling in relatively opposite directions, a driving member mounted to travel forward and back longitudinally of said belt runs, a pair of pawls carried by said driving member and interconnected for alternatively driving one or the other of said belt runs during the travel of said driving member in one direction, a second pair of pawls carried by said driving member and interconnected for alternatively driving one or the other of said belt runs during the travel of said driving member in the opposite direction, and reversible holding means for positioning said pairs of interconnected pawls with one pawl of one pair in driving relation to one run of the belt while one pawl of the other pair is in driving relation to the other run of the belt and vice versa.

4. A device of the class described, comprising a chain belt having parallel runs traveling in relatively opposite directions, a driving member mounted to travel forward and back longitudinally of said belt runs, a pair of pawls carried by said driving member and interconnected for alternatively driving one or the other of said belt runs during the travel of said driving member in one direction, a second pair of pawls carried by said driving member and interconnected for alternatively driving one or the other of said belt runs during the travel of said driving member in the opposite direction, and reversible holding means for positioning said pairs of interconnected pawls with one pawl of one pair in driving relation to one run of the belt while one pawl of the other pair is in driving relation to the other run of the belt and vice versa.

5. A device of the class described, comprising a chain belt having parallel runs traveling in relatively opposite directions, a driving member mounted to travel forward and back longitudinally of said belt runs, a pair of pawls carried by said driving member and interconnected for alternatively driving one or the other of said belt runs during the travel of said driving member in one direction, a second pair of pawls carried by said driving member and interconnected for alternatively driving one or the other of said belt runs during the travel of said driving member in the opposite direction, and reversible holding means for positioning said pairs of interconnected pawls with one pawl of one pair in driving relation to one run of the belt while one pawl of the other pair is in driving relation to the other run of the belt and vice versa, said holding means comprising shiftable abutment means and individual springs interposed between each said

pawl and said abutment means for yieldingly holding the pawls in their respective belt-driving positions, each said pawl being shaped to cam itself out of driving relation with the belt when the driving member reverses its direction of travel from the respective driving direction for which such pawl is held.

5. A device of the class described, comprising a chain belt having parallel runs traveling in relatively opposite directions, a driving member mounted to travel forward and back longitudinally of said belt runs, a pair of latch bars carried by said driving member and each disposed transversely to the direction of travel thereof and slidably lengthwise from a position of driving relation to one run of said belt to a position of driving relation to the other run, reversible holding means to position said latch bars for simultaneous driving relation to respectively different runs of said belt, one of said latch bars having its opposite ends both formed to serve as pawls to have driving relation to respective belt runs during one direction of travel of said driving member and to be cammed out of such driving relation during the other direction of travel of said driving member, the other latch bar having its ends both formed to serve as pawls for driving relation to their respective belt runs only during said other direction of travel of said driving member and to be cammed out of such relation during said one direction of travel, and reversible holding means for causing one of said latch bars to coact with one of said belt runs and the other said latch bars to coact with the other said belt run, and vice versa.

6. A device of the class described, comprising a chain belt having parallel runs traveling in relatively opposite directions, a driving member mounted to travel forward and back longitudinally of said belt runs, a pair of pawls carried by said driving member and interconnected for alternatively driving one or the other of said belt runs during the travel of said driving member in one direction, a second pair of pawls carried by said driving member and interconnected for alternatively driving one or the other of said belt runs during the travel of said driving member in the opposite direction, and reversible holding means for positioning said pairs of interconnected pawls with one pawl of one pair in driving relation to one run of the belt while one pawl of the other pair is in driving relation to the other run of the belt and vice versa, said holding means comprising a pinion journaled on said driving member between said belt runs, a pair of racks respectively meshing with opposite sides of said pinion for movement in opposite directions to each other toward and away from each of said belt runs, and springs between said pawls and said racks for yieldingly urging the respective said pawls toward their belt-driving positions.

7. A device of the class described, comprising a chain belt having parallel runs traveling in relatively opposite directions, a driving member mounted to travel forward and back longitudinally of said belt runs, a pair of latch bars carried by said driving member and each disposed transversely to the direction of travel thereof and slidably lengthwise from a position of driving relation to one run of said belt to a position of driving relation to the other run, one of said latch bars having its opposite ends both formed to serve as pawls to have driving relation to the respective belt runs during one direction of travel of

travel of said driving member and to be cammed out of such driving relation during the other direction of travel of said driving member, the other latch bar having its ends both formed to serve as pawls for driving relation to their respective belt runs only during said other direction of travel of said driving member and to be cammed out of such relation during said one direction of travel, and reversible holding means for causing one of said latch bars to coact with one of said belt runs and the other said latch bar to coact with the other said belt run, and vice versa, said holding means comprising a pinion journaled on said driving member between said belt runs, a pair of racks respectively meshing with opposite sides of said pinion for movement in opposite directions to each other toward and away from each of said belt runs, and springs between said latch bars and said racks for yieldingly urging said pawls toward their belt driving positions.

8. A chain belt drive, comprising an endless chain belt arranged to provide a pair of parallel runs moving in opposite directions, a crosshead mounted to reciprocate longitudinally between said runs, latch means carried by said crosshead and operative to drivingly engage one run of said belt when the crosshead moves in one direction and to drivingly engage the other run of said belt when said crosshead moves in the opposite direction, said latch means comprising a driving element shiftable from one run of the belt to the other run for alternatively driving such runs in one direction, and a second driving element shiftable from one run to the other for alternatively driving such runs in the opposite direction, means for reversibly shifting said driving elements to reverse the travel of the belt runs.

9. A chain belt drive, comprising an endless chain belt arranged to provide a pair of parallel runs moving in opposite directions, a crosshead mounted to reciprocate longitudinally between said runs, latch means carried by said crosshead and operative to drivingly engage one run of said belt when the crosshead moves in one direction and to drivingly engage the other run of said belt when said crosshead moves in the opposite direction, said latch means comprising a driving element movable on said crosshead from a position for driving one of said belt runs in one direction to a position for driving the other belt run in the same direction, and a second driving element movable on said crosshead between positions for driving said belt runs in the opposite directions, said elements being of ratchet pawl formation adapted to drive the respective belt runs in one direction of travel and to withdraw in the other direction of travel, and control means interposed between said driving elements adapted to engage them with respectively opposite runs of said belt for one direction of belt travel and to reverse their relation to the belt runs for the reverse direction of belt travel.

10. A chain belt drive according to claim 7, in which the springs are arranged in pairs bearing between abutments on respective racks and the opposite end portions of the respective latch bars so that the shifting of the racks positions the pawls for yielding relation to either belt run.

11. A chain belt drive, comprising an endless chain belt arranged to provide a pair of parallel runs moving in opposite directions, a crosshead mounted to reciprocate longitudinally between said runs, a double acting hydraulic motor pis-

ton connected to said crosshead for reciprocating the crosshead, latch means carried by said crosshead and operative to drivingly engage one of said belt runs when the crosshead moves in one direction and to drivingly engage the other said belt run when said crosshead moves in the opposite direction, said latch means being movable on said crosshead from a position for driving said belt in one direction of travel to a position for driving said belt in the reverse direction of travel through the reciprocating movement of said crosshead, means controlling said latch means to reverse the direction of travel of the belt as a whole, manually operative means for actuating said latch control means, valve means controlling the pressures on opposite sides of said

motor piston, and means actuated by said manually latch control means and coacting with said valve means to balance momentarily the pressures on said piston during the shifting of said latch.
